CLAIM

I claim the ornamental design for console ashtray, as shown.

DESCRIPTION

FIG. 1 is a perspective view of a console ashtray showing my new design;

FIG. 2 is a plan view of the top end thereof;

FIG. 3 is a plan view of the bottom end thereof;

FIG. 4 is an elevational view of the front thereof, the rear elevational view being a mirror image thereof; and,

FIG. 5 is an elevational view of one side thereof, the other side elevational view being a mirror image thereof.
